^{ATTORNEY.}

UNITED STATES PATENT OFFICE.

JOHN A. FERN, OF CINCINNATI, OHIO.

DESIGN FOR A PHONOGRAPH-CASE.

57,828.

Specification for Design.

Patented May 10, 1921.

Application filed August 2, 1920. Serial No. 400,876. Term of patent 7 years.

To all whom it may concern:

Be it known that I, JOHN A. FERN, a citizen of the United States of America, and a resident of the city of Cincinnati, in the county of Hamilton and State of Ohio, have invented a new, original, and ornamental Design for a Phonograph-Case, of which the following is a specification, reference being had to the accompanying drawing, forming part thereof.

In the drawing,

The figure is an isometric view of a phonograph case, showing my new design.

I claim:

The ornamental design for a phonograph case, as shown.

Witness my hand at the city of Cincinnati, in the county of Hamilton and State of Ohio, this 31st day of July, 1920.

JOHN A. FERN.
